CLAIM

The ornamental design for a bottle, as shown and described.

DESCRIPTION

FIG. 1 is a perspective view of a bottle showing our new design;

FIG. 2 is a second perspective view thereof;

FIG. 3 is a front view thereof;

FIG. 4 is a rear view thereof;

FIG. 5 is a right view thereof;

FIG. 6 is a left view thereof;

FIG. 7 is a top view thereof;

FIG. 8 is a bottom view thereof;

FIG. 9 is a front view thereof showing a cap for environment only;

FIG. 10 is a left view thereof showing a cap for environment only; and,

FIG. 11 is a top view thereof showing a cap for environment only.

The evenly spaced broken lines of FIGS. 1-7 show portions of the bottle which form no part of the claimed design. The evenly spaced broken lines of FIGS. 9-11 show an environmental cap which forms no part of the claimed design.
